US00D996414S

(12) **United States Design Patent** (10) **Patent No.:** **US D996,414 S**
(45) **Date of Patent:** **** Aug. 22, 2023**

(54) **ELECTRONIC DEVICE**

(71) Applicant: **Apple Inc.**, Cupertino, CA (US)
(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/744,847**

(22) Filed: **Jul. 31, 2020**

Related U.S. Application Data

(63) Continuation of application No. 29/655,603, filed on Jul. 5, 2018, now Pat. No. Des. 892,111, which is a (Continued)

(57) **CLAIM**

The ornamental design for an electronic device, as shown and described.

DESCRIPTION

FIG. 1 is a front view of an electronic device showing our new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines illustrate environmental structure and form no part of the claimed design.

In FIGS. 1, 3, 4 and 6, the claim is directed to the solid line perimeter, the portions found within the solid line perimeter form no part of the claimed design.

1 Claim, 5 Drawing Sheets

Related U.S. Application Data

continuation of application No. 29/562,900, filed on Apr. 29, 2016, now Pat. No. Des. 825,551, which is a continuation of application No. 29/498,009, filed on Jul. 30, 2014, now Pat. No. Des. 759,006, which is a continuation of application No. 29/457,335, filed on Jun. 9, 2013, now Pat. No. Des. 713,405.
